UNITED STATES PATENT OFFICE

MICHAEL McCANN, OF WOODHAVEN, NEW YORK, ASSIGNOR TO GOTHAM KNITBAC MACHINE CORPORATION, OF NEW YORK, N. Y., A CORPORATION OF DELAWARE

APPARATUS FOR REPAIRING RUNS IN FABRICS

Application filed April 24, 1929. Serial No. 357,669.

One of the objects of this invention is the provision of a new and novel machine for repairing runs in knitted and woven fabrics.

Another object of this invention is the provision of an apparatus of the general nature and objects disclosed in the application of William H. Leavin and Samuel B. Leavin, Patent No. 1,708,675, patented April 9, 1929.

Another object of this invention is the provision of a machine in which the fabric containing a run which is to be repaired such as a stocking is placed upon a supporting member having two spaced bars so that the cross threads which traverse the run lie in the teeth thereof.

A further object of this invention is the provision in a machine of the above type of a head having a vertically reciprocable or oscillatable needle mounted therein which is adapted to be moved longitudinally in the spacer bars in a step by step movement so that the needle will descend between the transverse threads and effect a repair of the run.

A still further object of this invention is the provision of automatic means for stopping the movement of the head at a predetermined point in either direction.

A still further object of this invention involves a needle bar construction by means of which the needle may be pointed in either of two directions so that a run may be repaired from either end.

These and many other objects as will be apparent from the detail disclosure to be given hereinafter are successfully sought by means of this invention.

This invention resides substantially in the combination, construction, arrangement and relative location of parts all as will be set forth in greater detail below:

Figure 1 is a top plan view of the device of this invention;

Figure 2 is a front elevational view of the device;

Fig. 3 is a right hand elevational view of the machine with a portion of the head broken away;

Fig. 4 is a left hand elevational view of

the machine with the stocking supporting form removed;

Fig. 5 is an enlarged elevational view of the operating mechanism at the left hand end;

Fig. 6 is an enlarged detail view showing the clamping means for holding the stocking in place on the spacer bars;

Figs. 7 and 8 are enlarged detail views of the construction of the nut which drives the head;

Fig. 9 is a central longitudinal cross-sectional view through the automatic stopping pin which opens the nut; and,

Fig. 10 is an enlarged plan view of the spacer bars with a stocking mounted thereon.

The general purpose of this invention is the provision of another form of machine of the type disclosed in the above patent by means of which runs in knitted and woven fabric, such as ladies' stockings may be repaired. As disclosed in that patent, the knitting needle oscillates or reciprocates in a vertical path while the run of the fabric is presented thereto in step by step motion. This machine differentiates broadly from that machine in that the run of the stocking is supported in a fixed position and the head on which the vertically oscillatable needle is supported, moves longitudinally of the run in step by step movement to effect the same result, namely a repair of the run.

In order to clearly understand the invention and this distinction, reference will be made in detail to the drawings. The machine is shown as comprising a base plate 1 having supporting standards 2 and 3 at each end firmly secured thereto. Journaled in these standards is a rotatable shaft 4 having a longitudinal slot or groove 4a and having secured thereto the driving pulley 5. Mounted to slide along this shaft is a hollow head 6. Also journaled in the standards below the shaft 4 is a threaded shaft 7 which passes through openings in the lower end of the head 6.

The two halves 8 of the nut supported within the lower end of the head 6 for engaging with the threads on the shaft 7 are shown in a similar relation in Figs. 2 and 3 and will be described in detail later. A small rod 9

is also supported in the standards on which are slidably mounted the arms 10. The outer ends of these arms 10 as clearly shown in Fig. 6 are provided with downward projections 12 which form a jaw by cooperation with the finger 13 pivotally supported on the outer end of the arm 10. A flat spring member 14 mounted on the arm 10 resiliently engages the upper end of the finger 13 and is held there by means of the pin and spring 15.

The spacer bars 16 having the teeth 16a on the upper edges thereof are held in spaced relation by means of a plate 17 which lies between them and to which they are secured. Enclosing these plates and engaging them a short distance below their upper edges is the elliptically shaped form 18. Secured to the plate 17 as shown in Fig. 2 is a plate 19 which is pivotally supported on the pin secured in the plate 20 which is in turn attached to the standard 3.

By means of this construction the spacer bars may be swung outwardly as indicated by the dotted lines in Fig. 1 so that the fabric to be repaired can be easily put in place.

Within the head 6 and encircling the shaft 4 is a cam 21 which is engaged by the forked ends 22a of the lever 22 which is pivotally supported at 23 on the head and within it. This cam 21 has a pin 21a secured thereto which rides in the slot 4a of shaft 4. The end of lever 22 is provided with a transverse pin 24 which fits in the slotted end of the member 25, which, in turn engages the collar 26 secured to the vertically movable needle bar 27. The lower end of the needle bar is provided with a small screw for holding the needle 29 therein. The exact structure of this needle is not described here since it is of the type disclosed in the patent mentioned above. In general, it is hooked at its lower end and provided with a spring pressed latch. Encircling the needle bar 27 is a bushing 33 having a large portion 30 thereon which engages the spring 32 between it and the head. The enlarged portion 30 is slotted and engages with the pin 31 secured to the needle bar 27. The lower end of the bushing 33 is encircled by a collar 34 having the handle 35. Since the head moves both to the left and right, it is necessary to be able to swing the needle 29 through an angle of 180° which is accomplished by means of the handle 35 and collar 34.

Secured in the lower end of the head 6 on the pivot pin 36 are the two halves 8 of a threaded nut which engages the threads on the shaft 7. These two halves are urged together by means of the spring 38 and are provided at their upper ends with the wedge shaped portions 39.

A pin 40 slidably supported in the head 6 is provided as shown in Fig. 9 with recesses to receive the wedge shaped portions 39.

When the pin is in the position shown in

Figs. 8 and 9, the two halves 8 of the nut are drawn together so that they engage the threads of the shaft 7. When the pin is moved either to the right or left so that the wedge shaped portions 39 ride up on to the cylinder portion thereof, the two halves 8 are open as shown in Fig. 7.

At the other end of the machine the shaft 4 is shown provided with a cam 45 which is partly encircled by the cam followers 47 and 50. Cam follower 50 has secured thereto, a finger 51 and cam follower 47 has secured thereto, the finger 48. Finger 48 engages the ratchet wheel 49 and finger 51 engages the ratchet wheel 58. As shown in Fig. 5 these ratchet wheels are arranged so that their teeth point in opposite directions. They are secured to the shaft 7. The cam followers 47 and 50 are drawn toward each other by means of spring 46. Pivotedly supported at 55 on standard 2 are the fingers 52 and 53, which are drawn towards each other by means of spring 54. Also pivotally supported on the standard 2 is the lever 56 which is secured to a cam 57 which engages the fingers 52 and 53 depending upon in which direction it is pointed. The operation of the device will now be given, assuming for purposes of illustration that the fabric to be repaired is a lady's stocking. The spacer bars 16 are swung outwardly and the stocking is telescoped thereover so that the threads which extend transversely of the run lie between the teeth 16a, one thread lying between two adjacent teeth. This is shown in Fig. 10 which is somewhat enlarged to clearly disclose the idea.

The spacer bars 16 are encircled by the stocking and the threads which traverse the run are shown at T, one line between each set of adjacent teeth on each bar. Of course, in the actual device, the thickness of the spacer bars at the teeth is not great since the run which occurs in such fabric is usually not very wide. The spacer bars are then swung back to the full line position shown in Fig. 1 and the arms 10 are swung down to the position shown more clearly in Fig. 5 so that the stocking is gripped against the spacer bars by means of the jaws comprising the fingers 12 and 13. These firmly hold the stocking in place under tension. We will assume that the head 6 is at the right as shown in Fig. 1. In order to move the head to the left it will be necessary to rotate shaft 7 in a counter clockwise direction when viewed from the end in Figs. 4 and 5. To accomplish this the lever 56 is in the position shown with the cam 57 forcing the finger 53 outwardly, which in turn moves finger 51 outwardly. Finger 51 does not therefore engage its ratchet wheel. Finger 48 does however engage ratchet wheel 49 and finger 52 is in a position to prevent any reverse or backward movement of the cam 49 as finger 48 is mov-

120
125
130

ing upwardly to engage another tooth. Pulley 5 is now driven from any suitable power source causing shaft 4 to rotate as well as cam 21, finger 3 and cam 45. The rotation 5 of cam 21 causes through the oscillation of lever 22, vertical movement of the needle bar 27. At the same time the rotation of cam 45 causes an up and down movement of finger 48 so that ratchet wheel 49 is rotated in a 10 step by step movement and rotates with it shaft 7.

The rotation of shaft 7 by reason of its engagement with nut 8 causes a step by step 15 movement of the head 6 to the left. As a result the needle 29 is presented step by step to the cross threads of the run so that it may descend between them in succession, effecting a knitting and interlocking of the transverse threads T, in a manner which has been described in more detail in the above mentioned 20 patent. If the run is of sufficient length to permit it the head 6 continues to move to the left until pin 40 strikes stop 42. This holds the pin 40 against movement and head 6 continues so that the halves 8 of the nut move 25 up the inclined recess in the pin 40 until the wedged ends 39 thereof ride up on the cylindrical portion of the pin. The nut then disengages the threads on the shaft 7 and the 30 head stops even though shaft 7 continues to rotate. A similar result is secured in the movement of the head in the opposite direction when pin 40 strikes stop 41, Fig. 2. For this reverse movement of the head it is necessary to turn the needle 29 so it is pointed 35 in the opposite direction which is accomplished by means of the handle 35.

From the foregoing disclosure it will be apparent that I have devised an exceedingly 40 new and novel arrangement by means of which runs in woven and knitted fabrics may be rapidly and accurately repaired.

I am, of course, well aware that many 45 changes in the details of construction and relative arrangement of parts will readily occur to those skilled in the art without departing from the principles and construction of my device and I do not therefore desire 50 to be limited to the disclosure given for purposes of illustration but rather to the scope 55 of the invention as it is defined in the appended claims.

What I seek to secure by United States Letters Patent is:

1. In an apparatus for repairing runs in 60 knitted fabrics, the combination comprising means for supporting the fabric, so that the threads which traverse the run are held in spaced relation, a vertically reciprocable 65 needle bar supported to move between said transverse threads, means for reciprocating the needle bar and moving it longitudinally of said means for supporting the fabric and means for automatically interrupting the

longitudinal movement of the needle bar in either direction.

2. In an apparatus for repairing runs in 70 knitted fabrics, the combination comprising toothed means for supporting the fabric so that the threads which traverse the run are held in spaced relation, a vertically oscillatable bar for supporting a needle arranged so that the needle will descend between the 75 transverse thread, means for oscillating the bar and moving it longitudinally and means for manually rotating the needle bar through 180° so that the needle will point in the proper direction depending on the direction of the longitudinal movement of the bar.

In testimony whereof I have hereunto set my hand on this 20th day of April, A. D. 1929.

MICHAEL McCANN.
